S. HULL.

Harvester Cutter.

No. 37,073.

Patented Dec. 2, 1862.

UNITED STATES PATENT OFFICE.

STEPHEN HULL, OF POUGHKEEPSIE, NEW YORK, ASSIGNEE TO HIMSELF
AND ISAAC W. WHITE, OF SAME PLACE.

IMPROVEMENT IN HARVESTERS.

Specification forming part of Letters Patent No. 37,073, dated December 1, 1862.

To all whom it may concern:

Be it known that I, STEPHEN HULL, of Poughkeepsie, in the county of Dutchess and State of New York, have invented a new and useful Improvement in Cutting Apparatus of Harvesters, &c.; and I do hereby declare that the following is a full, clear, and exact description of the same, reference being had to the accompanying drawings, forming part of this specification, in which—

Figure 1 is a transverse sectional perspective view of my invention. Fig. 2 is a transverse section of the same in the line $x-x$ of Figs. 1 and 4. Fig. 3 is a similar section in the line $y-y$ of Fig. 1, the cutters being removed. Fig. 4 is an inverted view of the cutting apparatus. Fig. 5 is an inverted view of the cutters. Fig. 6 is a front view of the cutting apparatus.

Similar letters of reference in each of the several figures indicate corresponding parts.

In the use of harvesting-machines one of the greatest difficulties to contend with is the clogging and ineffectual operation of the cutting apparatus, which combines the finger-beam, the guard-fingers, the knives, and the knife-rod. The greatest step to remedy this difficulty was made by Obed Hussey when he designed the open guard-finger in combination with the scalloped sickle. His plan prevents clogging above the cutters. Since Hussey's invention many plans have been devised to prevent clogging below the cutters.

Now, my invention consists in modifying the Hussey guard-finger in such manner that, while I secure the advantages of the open guard, I also effectually prevent clogging below the knives. To this end I have made the guard-finger substantially as hereinafter described.

To enable others skilled in the art to make and use my invention, I will proceed to describe the same.

A represents the finger-bar; B, the guard-fingers; C, the knife-rod, and D the knives.

The fingers B are spear-pointed, and are slotted through horizontally. The upper portion of the slotted fingers is partly cut away, and the slot is only covered for about half its length from the point of the finger by a short shield or stop, a. The bottom of the fingers

is on a curve from point e to heel or shoulder b, and from the base of the shoulder b to the top of the lower portion, d, of the slot e the finger widens and forms two wings, f f. In rear of these wings, and also of the body of the finger, an angular depression, n, and also a depression, i, on a bevel or slight curve, are formed, as represented, and from the terminus of this depression i a flange, j, is extended on a horizontal or nearly horizontal plane. Thus it will be seen that the plane of the lower portion of the slot e is much higher than the upper plane of the flange j.

The finger-bar A is made rectangular in form in its transverse section, except at its front lower corner, l, where it is beveled off or made with a slight curve, as represented, and it is also made plane—that is, without a groove in its top to receive the knife-rod—and thus friction is reduced.

To the under side of the finger-bar the flanges B are rigidly fastened, as shown at m, and the bevel-depression i fits the bevel l of the finger-beam, and thus it has a broad substantial bearing, and therefore the beveling of the under portion of the wings of the guard-fingers does not weaken the strength, but obviates the necessity of making the guard-fingers as heavy as is usual in cutting apparatus which have not the bevel l on the finger-beam, but have simply a curve on the wings.

The slant, curve, or under bevel, g', is very essential, as it prevents the guard-fingers and finger-bar from catching stones and from shoving the dirt, &c., up in front and between the guards, it allowing the finger-beam to float or slip easily over the obstructions. The slant also obviates the necessity of making the guard-fingers as long as in ordinary cutting apparatus, and thus the guards will be stronger. The slant also renders practicable the attaching of the guard-fingers to the under side of the finger-beam, and at the same time of having the plane of the lower portion, d, of the slot e even with or above the plane of the finger-bar.

The guard-fingers are arranged on the finger-bar so that the corners of their wings f f bear against and support one another, while they unitedly stiffen and stay the finger-bar.

The knives D are fastened upon the upper

side of the rectangular or other suitable shaped bar or rod, C, and the angular depression *n* in the top of the wings *f f* receives the rod and guides it, while the knives rest upon the planes *d* of the fingers.

What I claim as my invention, and desire to secure by Letters Patent, is—

Constructing the guard-fingers A with four planes, *d n i j*, or the equivalent thereof, substantially as and for the purposes set forth.

STEPHEN HULL.
